UNITED STATES PATENT OFFICE.

WALTER F. KOKEN, OF ST. LOUIS, MISSOURI.

DESIGN FOR A HAIR-DRESSING CHAIR.

Application filed October 11, 1922. Serial No. 3,937. Term of patent 14 years.

To all whom it may concern:

Be it known that I, WALTER F. KOKEN, a citizen of the United States, residing at St. Louis, Missouri, have invented a certain new, original, and ornamental Design for a Hair-Dressing Chair, of which the following is a specification, reference being had to the accompanying drawing, forming part thereof.

The figure is a perspective view of a chair showing my new design.

I claim:

The ornamental design for a hair dressing chair, as shown.

WALTER F. KOKEN.
